UNITED STATES PATENT OFFICE.

CAMILLO SAVINO, OF NEW YORK, N. Y.

MOTOR.

1,420,864.

Specification of Letters Patent. Patented June 27, 1922.

Application filed July 21, 1921. Serial No. 486,491.

To all whom it may concern:

Be it known that I, CAMILLO SAVINO, subject of the King of Italy, and resident of Bronx, in the county of Bronx and State of New York, have invented certain new and useful Improvements in Motors, of which the following is a specification.

My invention relates to motors of the type in which a rotary driven element is caused 10 to rotate by action operating through shifting weights movable toward and away from the axis of the said rotary driven element, the present invention having particular reference to the construction and arrangement of the means for shifting the said weights.

The present invention has for an object to provide a novel and simple arrangement and mounting for the weights and the means 20 for shifting the same, and to generally improve the construction of motors of this type.

For further comprehension of the invention, reference will be had to the following 25 description and accompanying drawings, and to the appended claims in which the various novel features of the invention are more particularly set forth.

Figure 1 of the drawings is a side elevation of my improved motor.

Figure 2 is a plan view thereof.

Figure 3 is a detail sectional elevation showing particularly the weight guiding and shifting means, this view being taken 35 on the line 3—3 of Fig. 4.

Figure 4 is an enlarged fragmentary transverse section on the line 4—4 of Figure 1.

Figure 5 is a detail section on the line 40 5—5 of Figure 4.

Figure 6 is an enlarged fragmentary section on the line 6—6 of Figure 1.

Figure 7 is an enlarged fragmentary section on the line 7—7 of Figure 1.

45 In the present embodiment of the invention, the machine comprises a pair of side frames 10 each comprising a longitudinally extending top horizontal member and a series of legs 10', the latter being adapted to 50 be bolted to the floor, or other bed of the machine, as indicated at 11.

Supported in suitable bearings 12 midway between opposite ends of the frames 10 is a transverse shaft 13. Upon this shaft 13, between the side frames 10 is suitably fixed the hub 14 of a wheel 15 which carries the shift-

ing weights. The weights are slidably mounted on a series of radial rods 16 fixed at inner and outer ends respectively to the hub and rim of the wheel 15. These rods 60 are preferably disposed between and in alternation to the spokes 14' of the wheel.

The weights are shown at 17 and are in the form of sleeve like members through which the rods pass freely. Mounted on 65 the hub 14 in a common axial disposition with the respective rods 16, are a series of solenoids 18 through the hollow centres or core apertures, of which the rods 16 extend, the rods being smaller in diameter than the 70 said core apertures of the solenoids. For convenient mounting of the solenoids on the hub 14 the circumference of the latter is formed of polygonal shape to present a series of flat surfaces to which the solenoid 75 heads may be screwed or otherwise secured. The cores of the solenoids are shown at 20, being in the form of cylindrical members freely surrounding the rods 16 inwardly of the weights and connected to the latter by 80 rigid straps 21. The inner ends of these cores are preferably tapered as at 20'.

The solenoids 18 act to draw the weights 17 toward the centre of the wheel 15, while the weights are shifted to their outer positions as the wheel rotates by engagement with a pair of circular tracks arranged eccentric to the wheel 15, one on each side thereof and preferably mounted in a manner to permit of adjustment to move their 90 centres toward or away from the axis of the wheel.

These tracks consist of a pair of rings 22, fixed by suitable brackets such as 23, to a pair of skeleton-formed rectangular slides 95 24 which are mounted on the side frames 10 to be adjustable in unison longitudinally thereof. To this end, a pair of horizontal guide rails 25 are bolted to the inner faces to the legs 10' of the side frames and having 100 the slides 24 resting thereon; co-operating tongue and groove guide elements 26 being formed on the contacting faces of the slides and rails to guide the slides on the rails. The slides 24 may be locked, in adjusted position, to the side frames 10 by means of bolts 27 passing through longitudinal slots 28 in the side frames and engaging in the vertical elements of the slides 24. To adjust the slides 24 in unison along the rails 25, I 105 provide a U-shaped yoke 30 which has its legs fixed to the slides 24 by bolts such as

31 and has its web formed with a boss 32 through which is threaded a screw 33 swiveled as at 34 in a U-bracket 35 bolted to and between the side frames 10. The screw 33 has a handwheel 36 fixed thereto for purposes of rotation.

The means for effecting engagement between the track rings 22 and the weights 17 comprises a second pair of rings 38 enclosing 10 the rings 22 and rotating on the latter, having an anti-friction bearing therewith as indicated at 39. These outer rings 38 are rigidly fixed to the weights 17 by suitable means such as the rods 40 projecting 15 from sockets in the latter and secured at their outer ends by screws 41 to the rings 38.

As indicated by the wiring connections 45 and 46 in Figure 4, the solenoids 18 are preferably of the split coil type to increase 20 their power, these solenoids being energized at the proper times through the following means:

Mounted on the inside of one of the side frames 10 is a vertical plate 50 of insulating 25 material having an aperture 51 of larger diameter than the shaft 13 through which the latter passes. Fixed to the inner face of this plate 50, to be flush therewith, is a segmental contact member 52 which extends 30 through an arc corresponding in length and position to the arc of rotation during which each solenoid is energized. This contact 52 has an integral tail piece 53 to which the end of one of the main leads 54 is connected.

35 Fixed to the shaft 13, adjacent the plate 50, is a collar 56 of insulating material carrying a series of slidable contact studs 57 pressed by springs 58 against the plate 50, these contact studs 57 having the wiring 40 connections 45 to one side of the respective solenoid coils 18 attached thereto. Fixed on the shaft 13 on the opposite side of the hub 14 to the collar 56 is a second insulating collar 60 on which is mounted a metal ring 61 45 to which the wiring connections 46 from the opposite sides of the solenoid coils lead. Upon this ring 61 a stationary brush 62 bears, to which is connected the other main lead 63. Pulleys or fly wheels 64 may be 50 mounted on opposite ends of the shaft.

It is believed that the manner of operation of my improved motor will be readily understood from the above description. With the tracks 22 and their enclosing rings 38 55 in the eccentric position as shown, the weights 17, which move with the rings 38, are considerably further from the axis of rotation of wheel 15 on one side (as indicated in the drawings, the left) than on the other, producing a preponderance of turning 60 leverage on one side of the shaft 13 which will cause the latter to rotate, and with it wheel 15 as indicated by the arrows in Figures 3 and 5. During rotation, the studs 65 57 successively come into contact with the

contact segment 52, each pin as it engages the segment closing the circuit through the corresponding solenoid, the current passing through main lead 54, contact 52, stud 57, split solenoid connection 45, the solenoid 70 coils, split solenoid connection 46, ring 61, brush 62 and main lead 63. Each solenoid 18 remains energized as long as the corresponding stud 57 engages the contact segment 52, the length of this segment being 75 greater than the spacing of these studs so that one of the solenoids is energized at all times.

In Figure 3 of the drawings I have indicated by the line A the relative length and 80 position of the arc through which the solenoids are energized, which arc commences at a point where the weights 17 and solenoid cores 20 are approaching that side of the tracks 22 which is nearest the axis of the 85 wheel 15 so that the attraction of the cores 20 by the energizing of the solenoids will both act to draw the weights 17 inwardly toward the centre on that side (leaving a preponderance of turning leverage on the 90 opposite side due to the weights on the opposite side being moved outwardly by tracks 22) and also, by reason of the oblique relation of this portion of the tracks 22 to the intersecting radii of the wheel 15, the 95 pull exerted by the solenoid will result in a turning movement being exerted on the rings 38 and in consequence on the wheel. By this combined action of the weights 17 and of the tracks 22 and rings 38 a continuous 100 rotation of the shaft and wheel is obtained. The arc through which the solenoids are energized preferably terminates just short of the point where the tracks are nearest the shaft 13, leaving the weights 17 free to be 105 carried outward as they move toward the opposite side of the wheel.

Having thus described my invention what I claim as new and desire to secure by Letters Patent of the United States is as follows:

1. A motor of the class described comprising a rotor having a hub, and rods, radiating therefrom, a series of radially extending solenoids fixed to and spaced around 115 said hub and surrounding said rods, cores for said solenoids surrounding and slidable on said rods, weights slidable on said rods and rigidly secured to said cores, an eccentric circular track with which said 120 weights are engaged, and means comprising said solenoids operating along a portion of said track which approaches the centre of the rotor for shifting said weights inwardly.

2. A motor of the class described comprising a rotor having a hub, and rods, radiating therefrom, a series of radially extending solenoids fixed to and spaced around 125 said hub and surrounding said rods, cores 130

- for said solenoids surrounding and slidable on said rods, weights slidable on said rods and rigidly secured to said cores, an eccentric circular track with which said weights are engaged, and means comprising said solenoids operating along a portion of said track which approaches the centre of the rotor for shifting said weights inwardly, said solenoid means having a split coil.
- 10 3. A motor of the class described comprising a rotor having a hub, and radial rods extending outwardly therefrom, a series of radially extending solenoids fixed
- to and spaced around said hubs and surrounding the inner ends of said rods, cores 15 for said solenoids surrounding and slidable on said rods, weights surrounding and slid- able on said rods and rigidly connected to said cores, an eccentric circular track, a ring surrounding and adapted to revolve 20 on said track, and means attaching said weights to said ring.

Signed at New York, in the county of New York and State of New York, this 27th day of June A. D. 1921.

CAMILLO SAVINO.
